(57) **CLAIM**

The ornamental design for a leak indicator for an indwelling urinary catheter, as shown and described.

DESCRIPTION

FIG. 1 is a top perspective view of a leak indicator for an indwelling urinary catheter, the leak indicator having a concave end;

FIG. 2 is a bottom perspective view thereof, the leak indicator having a concave opposite end;

FIG. 3 is a front side elevation view thereof;

FIG. 4 is a back side elevation view thereof;

FIG. 5 is a left side elevation view thereof, the right-side elevation view being a mirror image;

FIG. 6 is a top plan view thereof;

FIG. 7 is a bottom plan view thereof; and,

FIG. 8 is an environmental perspective view showing the indicator for an indwelling catheter in a condition of use. The stippling shown in FIGS. 1, 2, 6, and 7 depicts a surface texture of an absorbent insert.

The broken lines in FIG. 8 depict environmental subject matter which forms no part of the claimed design.
